(57) **CLAIM**

The ornamental design for a baking pan, as shown and described.

DESCRIPTION

FIG. 1 is a front, top, right perspective view of a baking pan showing our new design;

FIG. 2 is a front, bottom, left perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof; and

FIG. 9 is an enlarged fragmentary view showing a portion (9) of FIG. 1;

FIG. 10 is an enlarged fragmentary view showing another portion (10) of FIG. 1;

FIG. 11 is an enlarged fragmentary view showing a portion (11) of FIG. 2;

FIG. 12 is an enlarged fragmentary view showing another portion (12) of FIG. 2;

FIG. 13 is an enlarged fragmentary view showing a portion (13) of FIG. 5; and,

FIG. 14 is an enlarged fragmentary view showing a portion (14) of FIG. 7.

1 Claim, 14 Drawing Sheets
